COMBINATION CASEMENT WINDOW HOUSING AND WINDOW OPERATOR

Donn C. Blanchard, North Miami, Fla., assignor, by mesne assignments, to Stanley Building Specialties Company, a corporation of Florida

Application July 13, 1955, Serial No. 36,949

Term of patent 14 years

(Cl. D10—10)

I claim:

The ornamental design for a combination casement window housing and window operator, as shown.
